UNITED STATES PATENT OFFICE

CHARLES HARTER, OF ST. LOUIS, MISSOURI, ASSIGNOR TO P. H. MURPHY COMPANY, OF NEW KENSINGTON, PENNSYLVANIA, A CORPORATION OF PENNSYLVANIA

CARLINE REINFORCEMENT AND LOAD-LIFTING ARRANGEMENT

Original No. 1,678,510, dated July 24, 1928, Serial No. 7,560, filed February 7, 1925. Application for reissue filed July 9, 1930. Serial No. 466,898.

The roof structure of some railway cars comprises a series of spaced carlines spanning the distance between the opposite side plates and supporting the roof proper, which roof consists of steel plates, a wooden structure or a composition of both wood and steel. It is common practice to throw a rope or chain over one of these carlines to raise the lading to assist in moving it into or out of the car, and the load imposed thereby distorts the carline causing a disarrangement of the roof parts which results in a leaky roof. Hundreds of thousands of such cars are in service to which my invention is applicable. Even for new cars, however, it is economically advantageous to use my device so that all of the carlines in a car, or in fact, a series of cars will be interchangeable.

The invention resides in providing means to reinforce the roof structure, which means also provides a place for attachment of a load lifting device by being positioned in spaced relation to the adjacent parts of the car so that a rope or chain of a load lifting device may be thrown over it and/or providing a place for attachment of an ice tong or similar mechanism of a load lifting device so that said means may also be used to assist in loading or unloading the car.

The invention reinforces the individual carlines to sustain vertical loads; obtains cooperation between the adjacent carlines to sustain horizontal loads; reinforces the roof framing against distortion in a horizontal plane. The means connecting the adjacent carlines are also beams and provide a place to attach a block and tackle or rope to raise the lading. These connecting means or load lifting beams extend longitudinally of the car so as to provide a large range of operation which is particularly advantageous if the lading is long, such as automobiles or rails; furthermore, the weight of the sustained lading is distributed to at least two reinforced carlines.

The connecting member or beam for attachment of load lifting device extends longitudinally of the car and is preferably located adjacent the center of the car or may be positioned near the side plate or one near each side

plate, or if desired, may be located in both or in all such positions and still come within the scope of this invention. It may be desirable to raise the load simultaneously from more than one point. The beams may extend the full length of the car and reinforce each and every carline or they may simply include a plurality of carlines and be located as desired. The preferred spacing is shown in Fig. 1. The carlines are preferably apexed or arched to provide a sloping roof to shed water, etc., and the beams are so positioned that their bottom portion is not lower than the ends of the carlines so as not to interfere with the vertical free inside height of the car which is measured from a horizontal plane at the juncture of the lower portion of the carlines with the side plates.

The end plate is the end carline of a railway car for all intents and purposes of this invention, therefore, no distinction is made in the claims herein. If it is inconvenient to support the beam 7 under the end carline 2 (or end plate) it may be supported by a strap 14, as shown in Fig. 6, or any other convenient means.

Another object is to obtain a plurality of trussed carlines having a common strut. This common strut also prevents the carlines from tilting or buckling.

In the drawings:

Fig. 1 is a longitudinal section along the center of a car with composite roof showing my device applied thereon.

Fig. 2 is a skeleton plan view of a railway car showing the preferred location of my device on the car.

Fig. 3 is a cross section of a car with composite roof showing my device applied thereon.

Fig. 4 is a cross section of a car with a composite roof showing a modification of my device applied thereon.

Fig. 5 is an enlarged detail of part of the device showing its relation to the middle of the carline.

Fig. 6 shows a means of supporting the device adjacent the end carline (or end plate).

Fig. 7 shows a skeleton plan view of a rail-

way car with the beam extending the full length of the car.

The usual parts of the car are shown where-
in 1 is the side plate; 2 the end plate; 3 the
ridge pole; 4 the purlins; 5 the roof proper
and 6 the carlines. Old cars have wooden
carlines, but the modern car is equipped with
a metallic carline (sometimes having a wood-
en filler).

In my arrangement I provide a beam 7
which extends longitudinally of the car below
the carlines 6 and spaced away from the roof
5. This beam 7 then serves as a place for
the attachment of a block and tackle or rope
13 so as to provide means for attachment of
load lifting device to assist in moving the
lading. This beam passes under a plurality
of carlines. Below each carline and parallel
thereto is a brace or strengthening member
8 which has its middle portion secured to the
beam (by rivets 9) and its extremities at-
tached to the carline (by rivets 10). The
beam is also secured to the carline by attach-
ments 11. By this arrangement the carline
25 is trussed because the brace 8 becomes a
tension member and the beam 7 a strut, there-
by reinforcing the carline 6 to sustain ver-
tical loads. However, any other brace or
member may be used to hold the beam 7 in
30 alignment and position. Conversely the
beam 7 holds the brace or members 8 in their
proper position. The beam 7 forms a com-
mon strut for the adjacent carlines and se-
cures cooperation between these carlines and
35 prevents them from tipping or buckling as
beams have a tendency to do under load.
The cooperation of the carlines and the beam
(or beams) reinforces the roof framing
against distortion in a horizontal plane.

Fig. 3 shows an arrangement having beams
extending adjacent the center of the car and
also other beams 12 extending longitudinally
40 of the car and positioned adjacent the side
plates 1. It will be noted that the braces 8
45 perform the further function of bracing (13)
the beam 12 and furnishing additional means
to secure it to the carline 6.

The accompanying drawings illustrate the
50 preferred form of the invention, though it
is to be understood that the invention is not
limited to the exact details of construction
shown and described, as it is obvious that va-
rious modifications thereof, within the scope
55 of the claims, will occur to persons skilled
in the art.

I claim:

1. In a railway car, the combination of a
60 roof, a plurality of carlines, each comprising
a tension and a compression portion, and a
member spaced below said roof extending
normal to said carlines and secured to each
of said tension portions.

2. In a railway car, the combination of a
65 roof, a plurality of carlines, each comprising

a tension and a compression portion, and a
member spaced below said roof extending
normal to said carlines and secured to each
of said tension and compression portions.

3. In a railway car, the combination of a
70 roof, a plurality of carlines, each comprising
a tension and a compression portion, and a
beam spaced below said roof extending nor-
mal to said carlines, said beam positioned
75 between said portions and secured to each
of said tension portions.

4. In a railway car, the combination of a
80 roof, a plurality of carlines, each comprising
a tension and a compression portion, and a
beam spaced below said roof extending nor-
mal to said carlines, said beam positioned
85 between said portions, and secured to each
of said tension and compression portions.

5. In a railway car, the combination of a
85 roof, and a plurality of trussed carlines hav-
ing a common strut member separated from
said roof.

6. In a railway car, the combination of a
90 roof, carlines, a beam secured to some of said
carlines extending substantially longitudinally
of the car, spaced below said roof, and
braces extending normal to said beam sec-
ured to said beam and said carlines respec-
tively.

7. In combination with a railway car hav-
ing a roof and carlines; means to assist in
95 moving a lading comprising a member sec-
ured to some of said carlines extending longi-
tudinally of the car positioned below said
carlines and separated from said roof, and a
brace below each carline secured to said mem-
ber and said carline so as to truss said carline.

8. In a railway car having a roof and car-
lines; the combination of means to assist in
100 moving a lading comprising a member secured
to some of said carlines extending longitudinally
of the car adjacent the center thereof
spaced below said roof, other members sec-
ured to some of said carlines extending longi-
105 tudinally of the car adjacent the sides thereof
spaced below said roof, and a brace below
each carline secured to each of said members
and the carline so as to brace each of said
members.

9. A railway car provided with a roof
110 frame including a ridge pole, and a plurality
of trussed carlines, each of said carlines in-
cluding a compression member below said
ridge pole, a tension member arranged below
said compression member and a strut com-
115 prising a connecting beam uniting said car-
lines, said connecting beam being arranged
longitudinally of the car and separated from
the ridge pole to provide a space for the re-
ception of a hoisting device.

10. A railway car having a roof frame in-
cluding a plurality of trussed carlines, each
comprising a compression member secured to
the roof, a tension member located below and
having its ends secured to said compres-
120 sion member.

member, and a connecting strut spanning the space between said trussed carlines, said strut being located entirely below the compression member of each carline so as to provide an open space above the strut, fastening means whereby said connecting strut is rigidly secured to the compression member of each of said carlines, and fastening means whereby said connecting strut is rigidly secured to the tension member of each of said carlines.

11. In a railway car having a roof and carlines; members strengthening certain of said carlines against vertical deflection, and additional members connecting said carlines and reinforcing them against lateral deflection, said additional member spaced below the roof so as to constitute means to assist in moving the lading.

12. In a railway car having side plates, the combination of a plurality of spaced carlines with their opposite ends attached to the opposite side plates, a load lifting beam extending longitudinally of the car and secured to the underside of the carlines, the bottom of said beam being not lower than the ends of the carlines, and a ridge beam resting upon said carlines so as to provide a space between the ridge beam and the lifting beam between the carlines.

13. In a railway car having side plates and end plates, the combination of a plurality of apexed carlines with their opposite ends attached to the opposite side plates, a load lifting beam extending longitudinally of the car and secured to the underside of the carlines and to both of the end plates, the bottom of said beam being not lower than the ends of the carlines, and a ridge beam resting upon said carlines so as to provide a space between the ridge beam and the lifting beam between the carlines.

14. In a railway car, the combination of a plurality of carlines, a longitudinally extending ridge pole above the carlines, and a longitudinally extending load lifting beam secured to said carlines so as to provide a space between the beam and the ridge pole.

15. In a railway car, the combination of a plurality of carlines, a longitudinally extending ridge pole above the carlines, roofing in a plane above said ridge pole, and a longitudinally extending load lifting beam secured to said carlines so as to provide a space between the beam and the ridge pole and between the beam and the roofing.

16. In a railway car, the combination of a plurality of apexed carlines, a longitudinally extending ridge pole above the carlines, and a longitudinally extending load lifting beam secured to said carlines so as to provide a space between the beam and the ridge pole, the bottom of said beam being not lower than the ends of the carlines.

17. In a railway car, the combination of a plurality of carlines, and a load lifting beam

positioned below in spaced relation to said carlines and extending normally thereto, said beam having a substantially vertical stem secured to said carlines and laterally extending flanges for attachment of an ice tong of a load lifting device.

18. In a railway car, the combination of a plurality of carlines, a load lifting beam positioned below in spaced relation to said carlines and extending normally thereto, said beam having a substantially vertical stem secured to said carlines and laterally extending flanges for attachment of an ice tong of a load lifting device, and means securing said flanges to said carlines.
